CLASP

Richard L. Rank, St. Louis, Mo.

Application June 27, 1945, Serial No. 601,848

5 Claims. (Cl. 24—248)

1

This invention relates to improvements in snap-acting, material-gripping clasps of general utility. The invention has for its principal objects to devise a quick releasable clasp of the above type which is readily operable to positively and effectively clamp material or articles, which is of simple, cheap and compact construction and which has no projecting edges to cause accidental opening of the clasp or discomfort to the user. The invention consists in the clasp and the construction and combinations and arrangements of parts hereinafter described and claimed.

In the accompanying drawings which form part of this specification and wherein like symbols refer to like parts wherever they occur,

Fig. 1 is a front elevational view of a clasp embodying my invention.

Fig. 2 is a side elevational view of said clasp,

Fig. 3 is a rear elevational view of said clasp,

Fig. 4 is a vertical longitudinal sectional view on the line 4—4 in Fig. 1,

Fig. 5 is a side elevational view similar to Fig. 2, showing the clasp opened,

Fig. 6 is a sectional view similar to Fig. 4, showing the clasp opened; and

Figs. 7, 8 and 9 are enlarged sectional views on the lines 7—7, 8—8 and 9—9, respectively, in Fig. 2.

My clasp comprises two opposing pressed-metal jaw members A and B movable so as to open and close for gripping material between them. The front jaw member A has side flanges 1 on its inner face and a rearwardly offset upwardly extending lug or extension 2 at its upper end that has a transverse strap receiving slot 3 therein. The side flanges 2 are punched at their upper ends to provide inwardly extending pivot bosses 4 thereon. Just below the pivot bosses 4, the side flanges are bowed or curved transversely to provide longitudinal grooves or pockets 5 along the inner faces thereof. The flanges 1 are preferably of uniform depth along the bowed portions thereof and gradually increase in depth to the lower end of the front jaw member A.

The back jaw member B has a narrow upper portion that fits between the side flanges of the front jaw member A and a flared lower portion that is of greater width than said front jaw member and has a transverse strap receiving slot 6 near its free lower end with inwardly extending material engaging prongs or teeth 7 along the upper edge of said slot. The narrow upper end portion of the back jaw member B has an extension 8 at the upper end thereof that is doubled back on the inner face thereof in spaced parallel

relation thereto. The doubled-back extension 8 of the back jaw member B passes around the pivot bosses 4 of the front jaw member A between said bosses and the rearwardly offset portion of the strap receiving lug 2 at the upper end of said front jaw member, thereby pivotally securing the two jaw members together at their upper ends. As shown in the drawing, the back jaw member B has a central longitudinal stiffening rib 9 along the inner face thereof and a similar rib 10 on the doubled-back extension 8 that is disposed opposite to and normally clear of the rib 9.

The doubled-back portion or extension 8 of the back jaw member B has projections on the longitudinal side edges thereof that are bent in the direction of said jaw member across but clear of the side edges thereof and are curved or bowed transversely to provide transversely yieldable locking tabs or tongues 11 having longitudinally convex outer side surfaces. The spring tongues 11 are normally spaced clear of the adjacent side edges of the back locking jaw or lever B. In the open position of the clasp, the width of the doubled-back portion 8 across the marginal locking tongues 11 thereof is slightly greater than the distance between the side flanges 1 of the front jaw A across the edges of the portions of said flanges that are bowed to form the pockets 5. Thus, when the clasp is closed to clamp material between the free ends of the jaws thereof, the spring locking tongues of the back jaw B ride over the edges of the pocket forming portions of the side flanges 1 of the front jaw A and are pressed laterally far enough to pass said edges and then snap into the pockets 5, thereby locking the clasp in closed position with the material gripped therebetween and engaged by the prongs 7 of the back jaw. The longitudinal ribs 9 and 10 on the back jaw B, while normally out of contact with each other, are pressed together to transmit the closing pressure directly between said jaw and the turned-under extension 8 thereof after the locking tongues 11 seat on the edges of the side flanges 1 of the front jaw and until said tongues snap into the pockets 5 in said flanges. When the clasp is opened, the spring locking tongues 11 of the back jaw B are pressed inwardly by the overhanging edges of the bowed pocket forming portions of the side flanges 1 of the front jaw A and thus ride out of the pockets 5 thereof.

The hereinbefore described clasp is simple and inexpensive and is easily operable to positively and effectively grip the material and to release

the same; and it has no projections that are liable to cause accidental opening of the clasp or discomfort to the user. The clasp is of strong and durable construction and may be quickly and easily assembled; and the snap-action of the resilient locking tongues 11 firmly holds the clasp in locking position and permits said clasp to be quickly and easily opened. The force required to cause the resilient locking tongues 11 to snap into the holding pockets 5 therefor is directly and positively transmitted between the back jaw B and its doubled-back tongue-carrying extension 8 by longitudinal ribs 9 and 10 which also serve to stiffen and strengthen said jaw and said extension.

What I claim is:

1. A clasp comprising two opposed jaw members pivotally connected at one end for gripping material between them, one of said jaw members having side flanges facing the other of said jaw members, said side flanges having recesses in the inner sides thereof, said other jaw member having an extension that is doubled back on one side thereof and has free side marginal spring tongues adapted to snap into engagement with said recesses when the clasp is closed.

2. The combination set forth in claim 1 wherein the doubled-back extension of said other jaw member is normally spaced therefrom and the opposing faces of said other jaw member and said extension have ribs thereon that are normally spaced apart but are brought into pressure transmitting engagement during the snap-action engagement of said tongues with said recesses.

3. The combination set forth in claim 1 wherein the doubled-back extension of said other jaw member is located on the inner side thereof and is normally spaced therefrom and the opposing faces of said other jaw member and said extension have longitudinal ribs thereon that are normally spaced apart but are brought into pressure transmitting engagement during the snap-action engagement of said tongues with said recesses.

4. A clasp comprising two opposed jaw members pivotally connected at one end for gripping material between them, one of said jaw members having side flanges facing the other of said jaw members, said side flanges having recesses in the inner sides thereof, said other jaw member having an extension that is doubled back on one side thereof and is adapted to seat flatwise against said first mentioned jaw when the clasp is closed, said doubled-back extension having free side marginal spring tongues facing in the same direction as said side flanges and adapted to enter therebetween and snap into engagement with said recesses when the clasp is closed.

5. A clasp comprising two opposed jaw members, one of said jaw members having side flanges with inwardly extending bosses at one end thereof and transversely bowed portions forming recesses in the inner side faces thereof, the corresponding end of the other of said jaw members having an extension that is doubled back along the inner face thereof and passes around said pivot bosses, said extension having free transversely curved spring locking tongues projecting from its side edges adapted to snap into said recesses when the clasp is closed, said other jaw member and the doubled-back extension thereof having longitudinal ribs on the opposing faces thereof that are normally spaced apart but are brought into pressure transmitting contact during the snap-action engagement of said tongues with said recesses.
